DESIGN FOR A DEVICE FOR EJECTING PASTE MATERIAL FROM COLLAPSIBLE TUBES

Herve C. Holly and John W. McCarthy, Lockport,
N. Y.

Application January 15, 1934, Serial No. 50,416

Term of patent 7 years

To all whom it may concern:

Be it known that we, HERVE C. HOLLY and JOHN W. McCARTHY, citizens of the United States, residing at Lockport, in the county of Niagara and State of New York, respectively, have invented a new, original, and ornamental Design for a Device for Ejecting Paste Material from Collapsible Tubes, of which the following is a specification, reference being had to the accompanying drawing, forming part thereof.

In the accompanying drawing:

Figure 1 represents a front end view of a device

for ejecting paste material from collapsible tubes, showing my new design.

Figure 2 is a side elevation of the same.

Figure 3 is a top plan view thereof.

Figure 4 is a perspective view of the same.

We claim:

The ornamental design for a device for ejecting paste material from collapsible tubes, as shown.

HERVE C. HOLLY.
JOHN W. McCARTHY.
